RUG.

No 17,118.

Patented Feb. 15, 1887.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 17,118, dated February 15, 1887.

Application filed January 15, 1887. Serial No. 224,490. Term of patent 3½ years.

To all whom it may concern:

Be it known that I, ADOLPH PETZOLD, a citizen of the United States, residing at Philadelphia, in the county of Philadelphia and 5 State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading features of my design consist in a representation of two dogs and a cat on a checkered ground and a floral representation in the background. At each end of the 15 rug is represented a curtain drawn in at the center and bottom, as shown.

What I claim as my invention is—

The design for a rug, consisting of the representation of two dogs and a cat on a checkered ground, a floral background, and a representation of a curtain at each end looped up in the center, all as shown in the photographic print.

ADOLPH PETZOLD.
